UNITED STATES PATENT OFFICE.

GEORGE M. HOLLENBACK, OF LOS ANGELES, CALIFORNIA, ASSIGNOR OF ONE-HALF
TO DAVID W. MCLEAN, OF LOS ANGELES, CALIFORNIA.

STERILIZER.

Application filed August 31, 1922. Serial No. 585,503.

This invention relates to sterilizers, and more particularly to sterilizers for dental and surgical instruments as well as razors and other barbers' tools and implements, 5 and instruments used in manicuring and chiropody, without corrosion and without subjecting them to sufficient heat to cause injury thereto.

A further object is the provision of a sterilizer which may be used for the sterilization of surgical dressings and disinfecting of clothing.

The invention has for its objects the provision of improvements of the general character stated, which will be superior in point of relative simplicity and inexpensiveness in construction, taken in conjunction with positiveness and effectiveness and convenience in operation, economy in use and service, increased protection against infection and septic transmission, all further in conjunction with sightliness in appearance and compactness in form.

The invention consists in the novel and useful provision, formation, combination, association and relative arrangement of parts, members and features, all as herein-after described, shown in the drawings, and finally pointed out in claims.

30 In the drawings:

Figure 1 is a front elevation partly sectioned and broken away for clearness of illustration, of a sterilizer constructed and organized in accordance with the invention;

35 Figure 2 is an end view of the same taken in the direction of the large arrow at the right of Figure 1;

Figure 3 is a similar view taken in the direction of the large arrow at the left of Figure 1;

40 Figure 4 is a partial fragmentary vertical longitudinal sectional view, taken centrally through the construction shown in Figure 1, parts being broken away;

45 Figure 5 is a transverse vertical sectional view taken upon the line 5—5, Figure 1, and looking in the direction of the appended arrows;

50 Figure 6 is a detail longitudinal vertical sectional view taken upon the line 6—6, Figure 2, and looking in the direction of the appended arrows; and

55 Figure 7 is a fragmentary view of a feature of the construction shown in Figure 4, in detached position, and illustrating the

mode of withdrawal of the work holder from the sterilizing chamber.

Figures 4, 5, 6 and 7 are upon enlarged scales.

Corresponding parts in all the figures are 60 designated by the same reference characters.

Referring with particularity to the drawings, A designates a liquid reservoir, B a sterilizing agent reservoir, C a sterilizing compartment, D a work holder, E a sterilizing agent chamber member adapted to act as a heating chamber for volatilizing the sterilizing agent drawn from the reservoir B, and F a heating chamber to contain liquid drawn from the reservoir A, which 70 liquid, water or other suitable fluid, is heated by a burner G; such heating chamber transmitting its heat by conduction and radiation to the heating chamber E, and to the sterilizing chamber C—all such members 75 jointly operating and performing in the practice of the invention.

H designates means controlling the supply and conduction of sterilizing medium 80 from the reservoir B to the chamber E where such medium is heated and its vapors are passed through a passage e to the sterilizing chamber C.

A pipe g establishes communication between the upper portion of the water reservoir A and a zone of the heating chamber or reservoir F at a pre-determined level in each, preferably adjacent the top of such chamber A; and h designates a pipe adapted to establish communication between the 90 lower portion of the reservoir A and a zone in the chamber F, preferably somewhat lower than the lower end of the pipe g; a valve k being provided in the pipe h for controlling the passage of liquid through 95 the same, all for purposes hereinafter set forth, such pipes being provided at one end of the casing of the reservoir A and the casing of the chamber F.

K designates end closure means of the sterilizing chamber C, whereby such chamber may be tightly closed for the sterilizing operation and readily open to access for insertion or withdrawal of objects to be sterilized. A gauge L is provided at one end of the reservoir A for permitting determination of the level of fluid therein, such reservoir being provided at the other end with a capped filling spout M. N designates a blow off pipe for the heating chamber F, to 100 105 110

exhaust steam therefrom. O designates a valve controlled blow-off for the sterilizing chamber C, whereby gaseous pressure therein may be dissipated therefrom prior to removing the closure K.

The sterilizer reservoir B is provided with a detachable check valve b. A pet cock f is provided for drawing off water from the communicating water reservoir A and heating chamber F.

The valve p, controlling the supply pipe n for the burner G is provided with a pointer 8 to be read in connection with a graduated sector or dial 9 which permits opening the valve to just the proper extent to properly supply the burner with fuel, such as gas, when such dial and pointer have been properly calibrated.

R designates an implement for withdrawing the work holder D from the sterilizing chamber C.

The sterilizing chamber C is confined within a preferably annular casing 10, which in turn is surrounded by a casing 11, which provides the heating chamber F as between such casings 10 and 11, the chamber E being confined within a casing 12 set into a tubular casing 13, ranging longitudinally through the lower portion of the chamber F. The reservoir A comprises an annular casing 13^a above the casing 11, and the reservoir B is provided in a tubular casing 14 above the casing 13^a, the casings 10, 11, 13, 13^a and 14 all being supported by end walls or upright plates 15 and 16, respectively, such plates serving to close the opposite ends of such casings excepting where open as herein set forth. The lower ends of the plates 15 and 16 are formed into feet 17 for supporting the standards or end plates 15 and 16, and the entire assemblage of features mounted in connection therewith.

The closure means K comprises a circular disc or plate 18, which fits into one open end of the casing 10, the same being provided with an outwardly ranging threaded stud 19; and a compressible disc or washer of rubber, cork or other suitable material, 19^a, is borne against the plate 18 by a further metallic washer or centrally perforated plate 20, having peripheral ears 21, adapted to enter into notches in a segmental extension 22 at the open end of the casing 10, being brought into such positions or released from such positions by hand pieces or knobs 22^a upon such plate 20. A hand piece or knob 23 is cored in its axis and provided with a fixed bushing 24, threaded to cooperate with the threads upon the stud 19. The plate 18 having been inserted within the casing 10, the washer 20 is turned to engage the ears of the notched extension 22 after which the knob 23 is operated upon to compress and outwardly expand the washer 19, tightly closing the open end of

the casing 10, thus sealing up the sterilizing chamber and the work in the holder D therein.

The holder D comprises a perforated trough within which the implement or other work is placed, the perforations permitting the vapors from the chamber E to have access to all surfaces of the work and effectively sterilize it.

The means H for controlling conduction of the sterilizing medium from the reservoir B to the chamber E where such medium is heated and vaporized, comprises a pipe 25 ranging downwardly from one end of the casing 14 and communicating with a passage 26 in a fitting 27 mounted upon the adjacent end of the casing 13^a, which passage communicates with the lower end of a vertical cylinder 28 from the lower end of which extends a passage 29 in the fitting 27, such passage being provided with a plug cock valve 30 and communicating in turn with a pipe 31 ranging downwardly and through the end plate 16 and within the casing 11 to the casing 12 of the chamber E. A plunger or piston 32 is mounted in the cylinder 28. The check valve b provided in the casing 14 is detachable so that the chamber B may be filled when such check valve is detached, and when the piston 32 is elevated the check valve opens, displacing fluid which is drawn down the pipe 25 and into the cylinder 28. When the piston 32 is lowered the check valve closes, and, the valve 30 having been properly adjusted, such fluid is discharged from the cylinder 28 into the chamber E through the pipe 31. Thus definite charges of sterilizing medium may be supplied to such chamber E as required.

The operation, method of use and advantages of the improvements heretofore described and disclosed in the drawings will be readily understood from the foregoing statement, taken in conjunction with such other disclosure. The reservoir A having been materially filled with water sufficiently to fill the chamber F substantially to the top with possibly a surplus supply in the reservoir A, the burner G is lighted and the heat thereof is imparted to the water in the heating chamber F, the heat of which in turn is imparted to the sterilizing medium in the chamber E and also to the sterilizing chamber C.

It will be observed upon reference to Figure 5 that the water is maintained within the chamber F at certain levels and that the water in the reservoir A will supply water to the chamber F under certain conditions. It will be observed that the pipes g and h are in communication with the reservoir A and the chamber F. The particular arrangement and relation that exists between the chamber F and the reservoir A through the medium of the pipes g and h forms a

vacuum system, whereby when the water or other liquid within the chamber F reaches a low point, more water will be admitted from the reservoir A into the chamber F through the pipe h. In other words, the flowing of water from the reservoir to the chamber F depends upon gravity and this gravity carries water from the reservoir A to the chamber F when the surface of the water within the chamber F drops below the port opening of the pipe h within the chamber F. This will tend to stabilize the entire system of heating the device and the water within the chamber F may be maintained at a constant temperature which is very desirable for a device of this character.

The sterilizing fluid which may be an alcoholic solution of formaldehyde, or at least some solution which vaporizes below the boiling point of water, is drawn from the reservoir B through the action of the pump H and from such pump forced through the tube 31 to the heated vaporizing chamber where it is vaporized and emitted into the drum producing a pressure in the drum. Reference to Figure 2 will show that the cylinder portion of the pump H is provided with graduations, and it is therefore possible to force a given amount of the sterilizing fluid into the vaporizing chamber, and thus by this method permit a definite amount of sterilizing fluid to be drawn within the pump and produce a proportionate pressure in the chamber C. When the plunger of the pump is raised to draw a definite charge of sterilizing fluid therein, the valve in the tube leading to the vaporizing chamber is opened, the plunger then depressed forcing the sterilizing fluid through the tube and into the vaporizing chamber. The vapor by being discharged into the sterilizing chamber produces a pressure in proportion to the size of the charge. Vapor when under pressure is much more penetrating and effective as a sterilizing agent than when used otherwise. My device is efficient, for the reason that the sterilization is produced by the combination of applied heat and the application of chemical vapor under pressure, with the result that the time of sterilization is reduced to a minimum.

The volatilized medium from the chamber E rises into the chamber C, where it passes into the holder D and acts upon the implement or other object therein. The closure means K are manipulated as required for obtaining access to the sterilizing chamber.

Before obtaining access to the sterilizing chamber it is preferable to open the valve O and in Figure 1 it will be observed that a suitable tube 33 may be joined with said valve and lead to a reservoir 34, within which reservoir is a neutralizing, deodorizing fluid, said tube having its end extending within said chamber and immersed in

the fluid just mentioned. Thus, when the valve O is open the sterilizing fluid which has expanded into a gas, is allowed to bubble through said fluid and prevent obnoxious odors being directed into the surrounding atmosphere.

It is obvious that various changes and modifications may be made in the practice of the invention, in departure from the foregoing description and the disclosure of the drawings, without departing from the spirit of the invention.

Having thus disclosed my invention, I claim and desire to secure by Letters Patent:

1. In apparatus of the character disclosed, a sterilizing chamber, and means for heating the same, comprising a liquid chamber surrounding the sterilizing chamber and a liquid reservoir in communication therewith, said liquid reservoir being plurally in communication with said liquid chamber at different levels of said reservoir.

2. In apparatus of the character disclosed, a sterilizing chamber, and means for heating the same, comprising a liquid chamber surrounding the sterilizing chamber and a liquid reservoir in communication therewith, said liquid reservoir being plurally in communication with said liquid chamber at different levels of said reservoir, and at different levels of said liquid chamber.

3. In apparatus of the character disclosed, a sterilizing chamber, and means for heating the same, comprising a liquid chamber surrounding the sterilizing chamber, and a liquid reservoir in communication therewith, said liquid reservoir being plurally in communication with said liquid chamber at different levels of said reservoir; and means for controlling liquid passage through one of said means of communication.

4. In apparatus of the character disclosed, a volatilizing chamber for sterilizing material, and means for heating the same, comprising a liquid chamber and a liquid reservoir in communication therewith, said liquid reservoir being plurally in communication with said liquid chamber at different levels of said reservoir.

5. In apparatus of the character disclosed, a volatilizing chamber for sterilizing material, and means for heating the same, comprising a liquid chamber and a liquid reservoir in communication therewith, said liquid reservoir being plurally in communication with said liquid chamber at different levels of said reservoir and at different levels of said liquid chamber.

6. In apparatus of the character disclosed, a volatilizing chamber for sterilizing material, and means for heating the same, comprising a liquid chamber and a liquid reservoir in communication therewith, said liquid reservoir being plurally in communication with said liquid chamber at different levels

of said reservoir; and means for controlling liquid passage through one of said means of communication.

7. In apparatus of the character disclosed, 5 a sterilizing chamber, a chamber for volatilizing sterilizing material in communication therewith, and means for heating said last named chamber; and means for conduction of sterilizing material to said last named 10 chamber; said last named means comprising a reservoir, and means of communication between said reservoir and said volatilizing chamber, a pump being provided in conjunction with said means of communication.
- 15 8. In apparatus of the character disclosed, a sterilizing agent chamber member, a ster-

ilizing agent reservoir, means in operative connection between said chamber and reservoir for drawing a definite charge of sterilizing fluid from the reservoir and forcing it 20 into the sterilizing agent chamber member, a sterilizing compartment having a connection with the sterilizing agent chamber member, and means automatically controlling the heating of said sterilizing compartment and 25 sterilizing agent chamber member to volatilize sterilizing agent in the sterilizing agent chamber member and to regulate the pressure of such volatilized sterilizing agent.

In testimony whereof, I have signed my 30 name to this specification.

GEORGE M. HOLLENBACK.
